UNITED STATES PATENT OFFICE.

ERNEST RICHARD ROYSTON, OF LONDON, ENGLAND.

NAVIGABLE VESSEL.

1,195,857.

Specification of Letters Patent. Patented Aug. 22, 1916.

Application filed June 4, 1915. Serial No. 32,247.

To all whom it may concern:

Be it known that I, ERNEST RICHARD ROYSTON, a subject of the King of England, residing at Donington House, Norfolk street, 5 Strand, London, in the county of Middlesex, England, have invented new and useful Improvements in and Connected with Navigable Vessels, of which the following is a specification.

10 This invention has reference to navigable vesesls, and more particularly sailing boats or yachts; and it has primarily for its object and effect to provide improvements in them by which their sailing speed shall be increased.

15 According to this invention a boat is constructed or provided locally at the bow portion, from a point at, or somewhat below the normal water line, up to the gunwale, or 20 near same, that is, the portion which is struck by waves, or which strikes and presses on the water in the ship rising and falling, due to the action of waves, with a pneumatic or spring structure which is capable 25 of being freely locally indented, and subsequently reexpanded to its normal condition; and the outside surface of this elastic and resilient structure is practically flush with the general contour of the vessel's surface; 30 and furthermore, this structure is placed within recessed or chambered out portions of the ship's main rigid hull portion, to which it is applied, so that the outer surface or skin of this pneumatic or spring structure, 35 whether completely smooth or slightly corrugated or waved, is, as stated, at the outside of it, flush with the general contour of the ship.

In a boat or ship so constructed, when 40 struck by waves, or striking or pressing on the water, the resistance of the waves or water to the progress of the craft is not so great as it otherwise would be and is, that is to say, in the case of a boat sailing against 45 the wind, or with a beam wind, in a choppy or more or less heavy sea, the impact between the bow of the boat, and the sea, is rendered less than were the bow rigid, as at present; and so the stopping or impeding 50 force of the waves or sea, due to their motion, and the movement of the boat, is reduced, and the speed of the boat correspondingly increased.

In effect, by the interaction of the sea and 55 the boat, the elastic and compressible bow is first compressed, and the force of impact

lessened; and when it lifts from the sea, or the sea leaves it, the elastic bow expands, and resumes its normal condition and size without causing a corresponding reaction, 60 counter to progress.

The preferred construction and arrangement of the elastic bows is a pneumatic one, wherein the outer part is a tubular chambered, or like structure, made, say, of canvas 65 and rubber, more or less similar to that of a pneumatic tire, or air cushion or bed, with a plurality of tubes or ways, which are filled with air, arranged fore and aft, the divisions between which are connected at their inner 70 edges to the metal or other framing or plating which would lie within the pneumatic structure, from the gunwale to below the water level, or to or near it.

In the drawings in which the invention is 75 illustrated, and in connection with which it will be further described, this special construction is shown in Figures 1, 2, 3 and 4. These figures represent in their order, a bow 80 of a yacht showing by the shaded part, the area of the pneumatic structure, a transverse section through the bow or forward portion, and the transverse sections showing details of the pneumatic structure. Fig. 5 shows a section or modification wherein elastic and resilient effects referred to are obtained by metallic springs. 85

Referring now to Figs. 1 to 4, the pneumatic structure area is shown by the shaded portion marked 1; and this as indicated extends fore and aft from the stem, or near it, to a point at or near the beam; but it may be extended a less distance; or it may extend a greater distance, such as from or near the stem to the stern, or with an intervening 90 portion of the usual rigid construction between the bow and stern pneumatic portions. 95

The skin of the ship proper is marked 2, and in the case shown in Fig. 2, it extends down from the gunwale on the outside for a 100 certain distance, and then is carried inward; and for the depth of the pneumatic structure this inward portion extends, and it is again carried outward near the bottom of the ship at the center; and in the recess portion thus formed by this indenting of the ship's plating and framing, the pneumatic portion—generally designated 3—is disposed and held. The outside surface, however, of the ship at this pneumatic part, is even, and 105 flush with the surface of the main plating 2, the pneumatic portion being provided at its 110

outer surface with rubbered canvas or like textile sheeting 4, which forms the outer skin.

The pneumatic structure between the skin 4 or sheeting 4, and the plating 2 (of whatever material this may be made), consists of textile envelops 5, within which pneumatic rubber or rubber and canvas inflating tubes 6 are disposed; and a part of these 10 textile envelops 5, is carried down inward toward the plating 2, so as to form divisions between the pneumatic tubes 6; and at these parts the inner edges of the envelops are fitted with thin metal grooved continuous 15 bars or splines 7 (suitably riveted or otherwise fastened on the edges of the textile envelops), having threaded rods 8, spaced at suitable intervals, and extending through the plating 2, and fastened by hand nuts 9; 20 by the screwing up of which the required adjustment of the pneumatic part can be effected. Metal and rubber or like washers 10 and 11, respectively, are disposed between the nuts 9 and the plating 2, to make a water 25 tight joint.

The width of the pneumatic portion will vary with different sizes of boats; the maximum probably being from 10 to 12 inches, with an average of about 4 or 5 inches.

30 In the case shown, the textile envelops or supports are formed in separate parts for each tube, and stitched together at the portions forming the divisions, as shown by the drawing; but if desired these envelops may 35 be made of continuous textile sheeting, being folded at the part that fits within the holding or securing bars or splines 7. The envelops or holders 5 may also at their crowns be secured by stitching to the skin 40 sheeting 4 where they come in contact with it, as indicated by the drawing.

The triangular spaces which are formed between the crowns of the adjacent envelops and tubes 5, 6 are furnished with a filling 45 12, so that the portions of the flexible skin 4 which lie between the points of contact of the crowns and itself, are supported from within, so that the whole of the interior of the skin 4 will be equally supported from 50 within, against the pressure of the water from without.

In Fig. 3, this lower triangular filling 12 is in the form of a pneumatic tube, which 55 will be inflated through a suitable inflating device, say inserted at one end in it, and passing through the plating 2 at the end of the recess for the pneumatic structure, so that it can be filled at this end or ends; or, the tubes 5 and 12 might be connected by a 60 short communicating tube, and the air supplied to the tubes 12 in this way.

The upper triangular filling 12 in Fig. 3 is shown in solid form, and will consist of cork filled into bags, or in other flexible 65 form, or of rubber sponge or the like.

The tubes 6 will be filled with air under suitable pressure, which will be low in comparison to that used in self-propelled vehicle pneumatic tires, as the whole area of the pneumatic structure or its skin is pressed 70 upon throughout, and not at points only; and this pressure will be equal in the horizontal planes under the different depths of immersion.

The air can be charged into the tubes 75 either through separate valves or fittings 13, similarly as pneumatic tires or these fittings 13 may be connected together through a system of pipes 14, through which compressed air will be supplied from a cylinder containing 80 it under compression, or by a pump.

Hand holes and doors 15 will be provided in the plating 2 at suitable points, so that the tubes 6, and the interior of the pneumatic structure can be got at, and the tubes 85 introduced and taken out as and when required.

A mode of connection of the flexible skin 4, with the rigid skin 2 of the ship, is shown in Fig. 4. It consists in providing a slight 90 recess in the skin 2, in which the edges of the skin 4 lie, and gripping the edges between a clamping plate 16, and the skin 2; the clamping being effected by bolts and nuts as shown; thus producing a practically 95 flush and smooth outer skin surface of the ship's side generally.

In the modification of the flexible and resilient structure shown in Fig. 5, metal 100 springs 20 are used in lieu of the pneumatic structure; and these are introduced between the outer plating 4, which say is of thin metal of a flexible character, and the skin 2.

In the case shown, the springs 20 are of spiral form, and extend between the plating 105 2 and cupped disks 21, which rest on, and are held in position on the plating 2 by pins 22 thereon; and the outward limit of extension and pressure of the springs 20 is governed by cords, chain, or the like, 23, connecting the disks 21 with the holding bolts 8, secured by hand nuts 9, similarly to the bolts described with reference to Fig. 3. In lieu, however, of spiral springs being used, the coach type of spring, or other suitable 110 kinds of metal or rubber or air balls, or the like, may be employed.

In the case shown, in Fig. 5, a slight recess or groove 24 is employed in the edge of the plating or flexible sheeting 4, to better 120 allow of the bending inward and outward of the plate when in use.

In the pneumatic structure shown in Fig. 3, the casing 5, and skin 4, are built up or connected, so that all the several parts are 125 in one piece or structure; but if desired, the outer skin portion 4 may be separate from the envelop 5, and as regards this pneumatic structure it is only an example, which is convenient and advantageous; and alterna- 130

tive structures, such as the air cushion or air bed type of pneumatic inflatable appliances may be employed as the pneumatic portions of the ship's structure.

5 In the case shown, the outer surface or skin of the pneumatic structure is smooth and of the general contour of the portion of the ship to which it is applied; but if desired, it may have slight corrugations or 10 waves, namely, at the parts where the tubes 6 bear on the skin 4, and the ridges of the corrugations may exist; while at the spaces between these parts or lines, the recesses or shallow troughs will exist. The actual outside surface of the skin 4 should be rubber, so as to have as low a skin friction in water as possible.

The tubes 6 may be in continuous form for the length of the pneumatic portion 1 (see Fig. 1), and they would lie preferably 20 longitudinally or in the direction of length of this pneumatic portion; or the tubes may be in the form of short lengths, disconnected or interconnected as desired.

25 The air under pressure in some of the tubes, may, if desired, be maintained at a higher pressure than others. For instance the tubes subjected to the greater hydrostatic pressure, due to the depth of immersion, may be charged internally under a greater pressure than those subjected to a less one.

In some cases the air compressed by the force of impact or pressure, between the 35 sea and the boat, is adapted to assist in propelling the boat; and this is accomplished by employing the pneumatic structure or system abaft the beam, and also in some cases at the stern, and connecting the pneumatic system at the bow and stern, or having them continuous or inter-connected, so that the compression of the bow portion causes the stern and after beam portions to expand, and produce a forward propulsion 40 effect. In such a case where, at the after part of the boat, a pneumatic structure is used, and serves this purpose, this part or the outer portion of it, may consist of rubber, without textile fabric, so that it will 45 expand to a greater extent when pressed outward by the compressed air within, and therefore be more potent in its re-active propulsive effect.

If desired, instead of the pneumatic structure being in one piece, as in the case shown 55 in the drawing, it may be made in two or more parts, divided off from one another in a horizontal or vertical direction, or both, but practically continuous so far as the 60 outside is concerned; and the outside of

the structure may be protected by metal bars extending across the skin 4, and fastened to the rigid skin 2, and disposed at required distances apart.

What is claimed is:-

65

1. A yacht or boat of rigid construction having locally at its bow portion on the rigid structure, a pneumatic structure adapted to be indented or pressed inward locally, as well as generally, by pressure due to the 70 action of the sea or water, and normally pressed outward by air under pressure, the air being contained in closed india rubber tubes or bags between the outer locally flexible and resilient sheeting or sheathing and 75 the rigid structure of the ship; substantially as described.

2. A yacht or boat of rigid construction having an elastic or flexible structure adapted to be indented locally, as well as generally, by the pressure of the sea or water, and resilient from within, and placed within recessed portions of the main rigid structure of the ship, so that the elastic or resilient portion does not project substantially 80 beyond the general contour and surface of the rest of the rigid portion of the ship, which portions are of normal or the usual rigid kind; substantially as described.

3. A yacht or boat having a pneumatic 85 elastic and resilient portion on the outside of the rigid portion comprising a plurality of air containing tubes or bags, and a flexible skin outside the said tubes or bags; the rigid normal structure of the hull of the 90 ship being on the inside of the said tubes or bags, and the outside skin being held and secured to the inside portion or structure at a multiplicity of points, so that the tubes or bags are retained under pressure without 95 extending the outer skin beyond the general curvature or contour of the ship's surface, and flush with the ship's surface; substantially as described.

4. A ship or yacht having at its bow portion from a point below the gunwale to a point on each side of the keel, a recess filled with an elastic and resilient medium, and having on the outside of same a locally 100 indentable skin or sheath, pressed outward by the said medium, and practically flush with the general contour of the other portions of the ship; substantially as described.

In testimony whereof I have signed my name to this specification in the presence 115 of two subscribing witnesses.

ERNEST RICHARD ROYSTON.
